UNITED STATES PATENT OFFICE

2,331,806

METHOD OF PRODUCING DETACHABLE CLEVISSES

Henry G. Shakespeare, Kalamazoo, Mich., assignor to Shakespeare Products Company, Kalamazoo, Mich., a corporation of Michigan

Application June 23, 1941, Serial No. 399,334

2 Claims. (Cl. 29—148)

This invention relates to improvements in methods of producing detachable clevises and particularly, to that class of clevises illustrated and described in the United States patent to Hathorn, No. 2,089,649, granted August 10, 1937; an object of the invention being to provide a novel method for effecting the economical, practical and rapid production of such clevises.

It is also an object of the invention to provide a method for production of the hereinbefore referred to type of clevis whereby the same may be effected with a material saving of labor, time and costs without in any manner whatsoever, sacrificing the advantageous features thereof or detrimentally altering construction and design.

In clevises such as disclosed by the patent to Hathorn, No. 2,089,649, it will be observed that the clevis *per se*, comprises fixed and rotatable sections or halves, the latter being movable with relation to the former to assure convenient and quick engagement and disengagement of connected parts or elements to and from the same. These clevis sections are constructed from several special sizes of steel stock. Each such section requires many set-ups for the different kinds of milling necessary to its particular production and moreover, since the utilized steel stock is preferably of stainless character, each effected milling operation must necessarily be followed by a burring operation before the piece can be returned to a fixture. In consequence, it will manifest itself to workers skilled in the art that material production costs are entailed.

Through the teachings and practicing of my improved method, I am enabled to produce clevises of the type referred to from a single size of steel stock; to greatly lessen or reduce the number of operations required for production of the clevises and hence, effect considerable reduction of overall costs. Clevises produced in accordance with the improved method, moreover, are possessed of characteristics and finish equally as efficient and satisfactory as those present in clevises of the hereinbefore indicated type.

Other and further objects of the invention will be in part obvious and in part pointed out hereinafter.

In order that the invention and its mode of practicing may be readily understood by those skilled in the art to which it appertains, I have, in the accompanying drawing and in the following detailed description based thereupon, set forth one illustrative embodiment of the invention.

In the drawing:

Figure 1 is a top view of the connector body, 55 2, it will be seen that two clevis halves, sub-

with a portion of the shank broken away, formed in one piece, and before being divided.

Figure 2 is a top view of the connector after being divided or saw cut, showing the clevis pin 5 and the locking sleeve in operative position under urge of the compression spring, said sleeve being shown in section.

Figure 3 is a detail in perspective of the spacer element which is positioned between adjacent portions of the divided parts of the clevis and shank to compensate for body area reduction; and

Figure 4 is a perspective view of a clevis produced in accordance with the improved method, 15 showing the movable clevis in open position and also, having the opposite end of the shank body broken away beyond the compression spring engaged shoulder thereon.

Having more particular reference to the drawing in connection with which like characters of reference will designate corresponding parts throughout, in the practicing of my improved method, I first produce a connector body 1, often-times wholly characterized as a clevis. The connector body 1 consists of a cross-sectionally circular shank 2 of appropriate length and diameter. A substantially U-shaped piece or clevis 3 is integral with or fixedly carried upon one end of the shank 2, and as will be noted, has a marginally opening pocket or recess 4 formed in proximity to the free end of one of its sides.

On the remaining end of the shank 2, I provide an annular shoulder 5, the purpose of which will be hereinafter more fully described. Suitable connecting means, fragmentarily shown and indicated by the numeral 6, is attached to the shouldered end of the shank 2 and as will be understood, provides for the connecting of the device to cables, wires, etc.

The connector body 1, above described, is produced from a solid piece of stock. In the illustrated form, it has been finished as regards all initial production milling and drilling operations.

The connector body 1, in the form illustrated in Figure 1 is now subjected to a final production operation, to-wit, the basal portion of the clevis 3 and a portion of the shank 2 are longitudinally cut by engaging a slitting saw therewith. This longitudinal slit in the shank 2 extends for an appropriate distance thereinto, whereupon a transverse saw cut is effected in and through one side of the shank 2 to the inner end of the longitudinal slit. By reason of the described character of cutting or slitting of the clevis 3 and the shank 50 2, it will be seen that two clevis halves, sub-

stantially symmetrically similar in shape are produced. The one clevis half, i. e., that half designated for convenience by the numeral 7, remains integral with the major or body portion of the shank 2, while the remaining clevis half, indicated for convenience by the numeral 8 is provided with a comparatively short shank section 9, substantially symmetrically similar to the adjacent portion of the shank body 2. The clevis half 8, with its shorter shank section 9, is arranged in juxtaposed relation to the clevis half 7 and the shank body 2; shank section 9, obviously, having nesting-like reception in the cut-away portion of the latter. To compensate for the body area reduction of the shank 2, caused by the described longitudinal saw slitting operation, I provide a spacer element 10, of size and shape approximately corresponding to that of the cut-away portion surface of the clevis half 7, and its shank body 2. The thickness of the spacer element 10 corresponds to the thickness of the slitting saw used in the longitudinal slitting operation. In consequence, it is obvious that said spacer element will compensate for the thus effected body area reduction, causing the overall dimensions of the halved clevis 3 and the shank 2 to correspond to their original size and shape.

Following the above set forth operations and assembly of the clevis halves 7 and 8 and their respective shank portions 2 and 9, a pivot pin 11 is transversely engaged through an intermediate part of the cut-away portion of the shank 2 and an adjacent portion of the shorter shank section 9, thus, it will be seen that the clevis half 8 is movable or pivotal with respect to the fixed clevis half 7, i. e., that clevis half upon the corresponding end of the shank 2.

In order that the clevis 3 may be connected to various devices, such for example as cables, wires, etc., a cylindrical pin 12 is disposed transversely of the outer portions of the opposite sides of the same, i. e., the clevis halves 7 and 8. The pin, at one end, has fixed mounting in the clevis half 7, while its opposite end portion is adapted to be engaged in the pocket 4 of the clevis half 8, particularly when this clevis half is swung or moved into parallelism or substantial parallelism to the clevis half 7. Thus, it will be understood that the ends (looped or otherwise prepared) of cables, wires, etc., may be engaged over the intermediate portion of the pin 12. Obviously, by reason of the pivotal mounting of the clevis half 8, the same may be swung to a position completely disengaged from the pin 12, thereby allowing the clevis to be conveniently and quickly detached from a connected element or vice versa—and by the same token, as conveniently and quickly attached to such element.

The clevis halves 7 and 8 are adapted to be interconnected when in their operative or relatively parallel relationship in order to give security to an effected connection. This is accomplished by slidably mounting a locking sleeve 13 on the shank body 2 and arranging a compression spring 14 between said sleeve and the hereinbefore described annular shoulder 5 on that end of the shank 2 opposite the clevis 3. Accordingly, it will be understood that the locking sleeve 13, under urge of the compression spring 14, will be moved over the cut-away portion of the shank 2 and the shorter shank 9, as illustrated in the Figure 2. Because of the snug engagement of said locking sleeve 13 over the just referred to

portions, the shorter shank 9 will be secured against pivotal movement with respect to the shank 2 and in consequence, the movable or pivotal clevis half 8 will be retained in engagement (through its pocket 4) with the adjacent end of the pin 12. To open the clevis for detaching purposes, it is only necessary that the spring pressed locking sleeve 13 be slid in a direction away from the clevis 3, completely exposing the shorter shank section 9 so that it may be pivotally moved.

From the foregoing, it will be understood that I have provided a novel and highly meritorious method of the production of clevises of the described type or types. The described method of production is such as to effect a material differential in the cost of manufacturing the construction of clevis herein shown and the construction of a clevis such as illustrated and described in the hereinbefore identified patent to Hathorn. Moreover, and equally important, the method permits of materially shorter production times or periods. Consequently, by the practicing of this improved method, materially greater production of clevises may be effected. The construction of clevises produced in accordance with the improved method is such that none of the advantageous features thereof are lost or sacrificed. A clevis constructed according to the teachings of the improved method is equally durable, efficient and strong as those forms of clevises manufactured from at least two special sizes of steel stock which must be individually machined, drilled and finished.

Whereas I have herein shown and described the shank 2 carrying but a single clevis on one of its ends, it will be understood, of course, that clevises constructed according to my invention may be, if conditions or preference so dictate, arranged on each end of the shank body 2.

I claim:

1. A method for producing detachable clevises, consisting of providing a clevis body including a substantially U-shaped outwardly opening portion and a longitudinally disposed shank integral with the inner and basal portion of said U-shaped portion; longitudinally cutting the basal portion of the U-shaped portion and a portion of said integral shank by a single cutting operation, transversely cutting one side of the longitudinally cut shank to meet the outer end of the longitudinally cut in said shank, and pivotally interconnecting said U-shaped portion and shank in juxtaposed relation.

2. A method for producing detachable clevises, consisting of providing a clevis body including a substantially U-shaped outwardly opening portion and a longitudinally disposed shank integral with the inner and basal portion of said U-shaped portion, longitudinally cutting the basal portion of the U-shaped portion and a portion of said integral shank by a single cutting operation, transversely cutting one side of the longitudinally cut shank to meet the outer end of the longitudinally cut in said shank, positioning a spacer element of predetermined thickness between the longitudinally cut basal and shank portions to compensate for the body area reduction thereof, and pivotally interconnecting said U-shaped portion and shank in juxtaposed relation.

HENRY G. SHAKESPEARE.
